UNITED STATES PATENT OFFICE.

GEORGE E. BUZZA, OF MINNEAPOLIS, MINNESOTA.

PROCESS OF REPRODUCING PICTURES OF ART SUBJECTS.

Application filed December 7, 1925. Serial No. 73,935.

My invention relates to a process of reproducing pictures and representations of art objects. It is the object of my process to reproduce in quantity and in the original 5 color of the artist paintings and other art objects which shall have the appearance of hand-brushed and colored art work, and to do this, even in large editions, as economically, or even more economically than can be done 10 with multi-colored printing.

In the practice of my process I apply a series of specially prepared stencils in rotation to a print proof or other reproduction of the original painting or drawing in 15 unicolor, i. e., black, gray or neutral tone, the stencils being applied so that a single color washed through the openings of the stencil will reach the particular portions of the proof which are designed to carry that 20 color. For each stencil, therefore, there is a special water color having distinct characteristics which is applied over and through the stencil by means of brushes having distinctive characteristics. The proofs are also 25 used as a base for cutting or preparing the several stencils, whereby the color effects are produced on the proof by successive application of each color made separately and individually through each individual stencil, 30 the colors being applied in rotation from the lightest color to the darkest. In this manner exact reproductions of the colors appearing on the original painting or drawing can be made, and not only that, but the colors 35 will be applied upon the reproduction in such a way as to closely simulate hand-brushing work. Also, colors and modifications of colors, can be used successfully by this process which cannot be applied by any 40 mechanical printing press or by any other known non-artist color application process.

In the printing operation the color is applied in the form of inks or water color pastes, which always must include certain ingredients that affect to some extent the character of the color reproduction. Inks, so-called, always include oil. This oil reacts upon the pigment either because of some slight modification of the pigment itself, or 45 because of color in the oil, and produces a distinct dulling of the color and diminution of the true color effect. If oil is not used, gelatins or other forms of paste are necessary, with the result that the color itself 50 as applied by printing never can be as pure and as correct in color effect as with hand

work. In addition to this, the color in printing must be impressed upon the paper. That is, the color is transferred from the plate surface in the press by means of pressure upon the receiving surface. This cannot produce the same characteristics of color application as is done by hand brushing, and this fact also affects the character of the 60 color reproduction. 65

Moreover, many of the better papers for art reproduction work, and particularly for certain kinds of art reproduction work, are those with rough surface, often even fuzzy in character. These surfaces are in nowise 70 injured or changed by the brushing in of color, and the color brushed in will flow freely to all parts of such surfaces that are exposed. On the other hand, when the color is put on by pressure in printing, first 75 it may not be quickly applied to all parts of the roughened surface, and, second, the pressure by which the effort is made to get the color to all parts of the roughened surface 80 has the effect of modifying or destroying that surface. 85

These disadvantages, wherein printed color reproductions differ from hand-brushed color reproductions to the detriment of the printed reproductions, are all overcome by my process, which, nevertheless, although a hand process, and in no sense a mechanical process, can be practiced with un-skilled labor, and, so, as economically 90 (and indeed much more so where small editions are employed) than color reproductions by printing. 95

The process in its entirety really involves the use of five sets of steps: (a) the preparation of the proof or print, which includes the formation of the registering sheets upon which the proof is printed and which are used both for the cutting of the stencils and the reception of the colors from the stencils; (b) the preparation of the stencils; (c) the preparation of the colors to be used with the stencils; (d) the application of the stencils to the proof sheets; and (e) the brushing in 100 of the colors as prepared, which latter step includes as a feature the use of brushes especially adapted for that purpose. 105

The drawings presented herewith illustrate an art subject, one of the stencils and the brushes employed in laying colors through these stencils. These figures are 110 illustrative only as the process may be practiced with a multitude of forms of art sub-

jects and of stencils and the brushes vary somewhat according to the character of the stencils employed.

In these drawings, Fig. 1 represents an original art subject as it appears from a print in unicolor ink. Fig. 2 represents one of the stencils which are employed. Figs. 3 to 6 inclusive represent the forms of brushes employed in connection with the work.

Preparation of the proof or print.

The proof or print is made in the usual way by photographing the art subject, preparing therefor a plate and taking impressions upon suitable sheets of paper as an important step in the practice of the process. However, these sheets of paper are preferably cut to exact size and all of them of the same size with true rectangularly-disposed edges and with the proof printed on all of the sheets in exactly the same relation to the edges thereof, that is, with identically the same margins around the edges of the proof. Obviously a single sheet may have thereon a multiplicity of proofs of the same art object, or a multiplicity of proofs of different art objects.

Not only are the sheets accurately sized and cut with the edges rectangular, but it will be advantageous to make in opposite corners, preferably the lower left-hand corner and the upper right-hand corner of all of the sheets registering, markings of exactly the same size and in the same position in each sheet. These markings may be triangular, as indicated at 10 in Fig. 1. Also the sheets may be punched to form circular holes through each sheet, as indicated at 11 in Fig. 1. The markings and the holes of the proof sheets, having the same fixed relation to the proof for each proof sheet, may be caused to register with similarly shaped and edged stencil sheets formed with openings similarly positioned on the stencil sheets to the markings and openings on the proof sheets, so that the several sets of stencils when prepared as hereinafter described may always be brought into the same relation to the proof for the brushing in of the colors.

Preparation of the stencils.

As indicated above, and as a preliminary step in the preparation of the stencils, the metallic sheets upon which the stencils are formed are preferably constructed of the same size as the proof sheets, having rectangularly-disposed edges and having openings formed in opposite corners in the same position as the markings and holes of the proof sheets, so that when a stencil sheet is positioned with these holes in registering position over the markings or holes of the proof sheet, the color openings in the stencil will register with the appropriate portions of the proof. For certain classes of

work the stencil sheets may be formed of copper, particularly where the sheet is considerably cut out and large runs are to be executed. In general, however, the preferred form of stencil sheet is a so-called zinc sheet, 70 although it, in fact, is an alloy of zinc and antimony in suitable proportions. These sheets are six mils, eight mils, ten mils, and in some instances thirteen mils thick, the thinner sheets being used for small cuttings 75 and details and the thicker sheets where the cuttings are larger or where the runs are very large.

In cutting the stencils a proof sheet is laid upon an uncut stencil sheet and secured thereto in any desired way. In some instances pasting together may be employed; but ordinarily if the proof sheet and the stencil sheet are each placed upon a board, preferably made of brass, having pins or other abutments extending through their corner openings, or having opposite corners held in right-angled abutments it will be unnecessary to use any paste.

A skilled artisan is required to cut the stencils, one who not only has the manual skill necessary, but who can determine from an inspection of the original painting what colors should be employed. It is first necessary to make that determination and to estimate the number of colors, which will give the number of stencils to be made, there being a separate stencil for each color. It is of course, not material in which order the stencils are cut, but since the colors are laid on from the lightest to the darkest and the stencils are so numbered, in practice, the stencils will be cut for the lightest colors first and consecutively through to the darkest colors. Using the original painting as a guide and following the demarking lines thereof as they appear on the proof, the artisan will cut through the proof and the zinc sheet along these lines, thus producing cut-out portions in the stencil. And this will be done progressively for each of the colors to be used, and after all have been prepared the stencils will be numbered and, preferably, colored on the back, thus indicating the several colors to be used and the order in which the stencils are to be used and these colors are to be applied. For the very small cut-outs, that is the fine detail work, ordinarily the thinner sheets will be employed and the cutting will be done directly through the proof and the zinc stencil sheet.

Where, however, the larger cut-outs are to be made, and it is necessary to use the thicker stencil sheets, direct cutting cannot be so effectively employed and the stencil is prepared by an acid-bath process. In working this process the zinc sheet is covered with a thin layer of paraffin before the proof is applied thereto. Using the same detail as is used in cutting through the thin

zinc sheets the artisan will merely cut through the proof sheet and the paraffin on the zinc sheet in demarking the boundaries of the colors for the successive stencils. 5 This sheet is then dipped into a bath of sulphuric acid diluted with sal ammonia, which results in etching the lines of color borders upon the zinc sheet, which etching may be continued until the pieces 10 demarked thereby can be withdrawn directly, or the etching may be carried on only long enough to mark out the lines which may be subsequently cut. The acid bath treatment is also effective for very fine openings, 15 as dots.

After the stencils are severally cut they must individually be rolled flat. This rolling must be done with great care so as not to injure delicate outlines. The rolling is 20 done for the purpose of eliminating the burr or slightly ragged lift on the reverse side of the stencil which is caused by the cutting. As above indicated, the complete list of stencils prepared in the above way are numbered consecutively from the first color to 25 be applied to the last, and the application of these colors is most effectively done by putting on the lightest colors first and successively going to the darker colors and applying 30 the darkest color last.

Preparing the colors.

As has been already stated, it is possible in this process to use a very much larger range of colors, and to use kinds of colors which cannot be applied to printing inks and be used in printing presses. The colors available for use in the process comprise thirty-eight vegetable colors and fourteen chemical colors, which carry the following names:

Vegetable colors.

Sepia naturelle.	Laque noire.
Bleu de Prusse.	Bleu Persan.
Terre de Sienna naturelle.	Ocre jaune.
Terre de Sienna brûlée.	Brun Van Dick.
Jaune de Chrome clair.	Jaune de Chrome foncé.
Jaune de Chrome moyen.	Jaune de Chrome orange.
Jaune Persan foncé.	Orange Persan clair.
Jaune Persan citron.	Rouge Persan ecarlate.
Jaune Persan clair.	Laque Geranium.
Rouge Vermillionne clair.	Rouge Persan foncé.
Rose Tyrion.	Laque Carminé.
Outremer foncé.	Pourpre.
Outremer clair.	Bleu de Cobalt.
Vert Lumière bleu.	Bleu Pervenche.
Cendre bleu.	Bleu d'Orient.
Vert Gui.	Vert Véronèse.
Vert émeraude.	Vert riche foncé.
Gris de Payne.	Vert Persan clair.
	Vert végétale.

Chemical colors.

Rhodamine extra pure.	Cárfhame.
Violet R. 3937.	Brun rouge No. 6626.
Mandarine.	Essuie extra.
Lilas bleutâtre pur.	Vert printemps.
Brun sepia No. 6627.	Jaune d'Or.
Noir 513.	Gris de Payne.
Turquoise.	Beige No. 6625.

Admixture of various colors gives an infinite variety of possible tints and tones between the various colors named.

65 The colors are those known as water col-

ors used by artists, and are mixed in the same way as water colors are mixed by artists. In any case they may be darkened by the introduction of black or sepia in such quantities as are desirable. They may be 70 lightened by mixture with plain or distilled water. In the practice of my process in addition to the use of water I mix milk into the colors to prevent froth and to settle such color as may rise with the froth and to prevent 75 the formation of additional froth. In general the relation of milk and water used in the diluting fluid is ten per cent (10%) to fifty per cent (50%) of milk to from ninety per cent to fifty per cent of water. 80

Also, since the colors must be applied very rapidly in order to make the process economical in practice, it is necessary to mix small quantities of gum arabic with the colors 85 after they are mixed to insure the colors adhering readily to the paper. The quantity of gum arabic used depends upon the texture of the paper used. If it has a rough, readily absorbent surface a relatively small amount of gum arabic will be sufficient. If the surface of the paper is smooth and shiny a considerable amount relatively of gum arabic is necessary. And if the paper employed has a greasy surface, as some art papers do have, I mix with the colors in addition to 90 the gum arabic varying quantities of ox gall, which produces characteristics to the color that enable it to readily adhere to such a greasy surface. 95

Applying the stencils and brushing in the colors.

The work of preparing the stencils and of preparing the colors to be used is, of course, all preliminary to the actual reproduction 100 of the art subject. This preliminary work must be done by skilled artisans, but obviously is not work requiring a very large amount of time or labor. The principal labor element in producing reproductions 105 of the art objects, especially in large editions, say from ten thousand to one hundred thousand copies, consists in the brushing in of the colors. And since each copy may have applied thereto fifteen, twenty, twenty-five, thirty or even more different colors, it 110 will be clear that the brushing in of the colors involves a very large labor element in which it is essentially desirable to eliminate so far as possible skilled labor and be able 115 to employ common, or unskilled, workmen. 120

It is an essential feature of my invention that it is possible to do this work of brushing in the colors with common or unskilled labor, and that in the practice of this part of my process the operator is not called upon to exercise any judgment at all, and only such skill as is requisite to apply the stencil to the sheet, brush quickly over the back of the stencil with the color and remove the 125 130

stencil and colored sheet, and repeat the operation. And the process facilitates these operations so that they may be performed substantially automatically by common labor having very ordinary intelligence and manual skill.

It is to be noted that each copy of the art object has as a base the printed proof heretofore referred to. The proof sheets will be furnished the operators in blocks of a suitable number and may be placed upon holders which have either corner posts or pins at the lower left and upper right corners respectively, and which may be adjustably held upon the board for adapting themselves to sheets of different sizes. The corner posts are each shaped with a vertical right-angled interior receiving opposite corners of the rectangular proof sheets. The pins are circular, of the same size as the round holes in the sheets and are adapted to extend through the registering round holes 11 of a multiplicity of proof sheets, thereby holding all of them in the same relative position.

The operative having a pile of proof sheets placed in registering position as above described will have a certain stencil and a certain color to apply to all of such sheets. The first step in the application of the color will be the placing of the pile of proof sheets in registering position upon the receiving board. The stencil will then be placed upon the board over the top sheet, the posts (whether it be the internal right-angled corner posts or the pins extending through the holes in the stencil) will hold the stencil always in exactly the position in reference to the proof in which the stencil was when the color portions were cut out therefrom.

The operative will be provided with the color suitable for the particular stencil, in practice a different operative and of course a different stencil being used for each different color. Also, the operative will be provided with a brush suitable for applying color through the stencil. In general where there is any considerable degree of opening in the stencil, or where the openings are of considerable degree of length, brushes, such as are shown in Figs. 5 or 6, will be employed, the large brush of Fig. 6 being used for so-called large openings and the smaller brush of Fig. 5 for somewhat smaller openings. The brush of Fig. 5 is much used as it may be held in the bottom of the hand. For still smaller work a brush such as shown in Fig. 4 may be employed. It is to be noted that each of these brushes, as shown in Figs. 3, 4 and 5, are characterized by having a perfectly flat brushing surface, which is an essential feature of my process for producing efficient work by unskilled labor. Occasionally, where a stencil has only a very fine line, a pointed brush, such as is shown in Fig. 3, may be employed.

The operative will be provided with a pot or receptacle containing the color which will be applied from time to time to the surface of the brush. Also, a second receptacle such as an ordinary china plate with a liquid therein consisting of a more or less concentrated solution of gum arabic, or in some cases of gum arabic with ox gall added, as hereinbefore pointed out. Also, either alone or in conjunction with gum arabic, the albumen of the white of an egg is frequently used. The purpose of each of these additions is to make the color quickly adherent and quick drying, thereby insuring a perfect covering of the color and avoiding liability of smearing in the laying up of the newly colored sheets. The color will be worked into the surface of the brush by moving the same about upon a color board, the color itself being kept in as dry a state as possible. Owing to the flat, compact nature of the surface of the brush a very large amount of color can be concentrated at the ends of the bristles.

After sufficient color has been worked into the brush the operative will dip the brush into the very thin film of liquid above described upon the plate, giving it one short movement there, and then will move the brush across the stencil back and forth to cover all openings therein. Ordinarily the entire brushing action is accomplished with one or two movements of the brush. The stencil is then lifted up, the colored sheet withdrawn, the stencil dropped back into place and the operation repeated.

If there is any substantial running of the color at the edges of the stencil openings it will tend to overlap margins of color and render the reproduction indistinct and ineffective. To prevent running of the colors the back of the stencil is covered with an exceedingly thin film of grease, which must be renewed frequently. Any desirable means of putting this thin film of grease upon the back of the stencil may be employed, but I have found that in practice the very best results are obtainable from using salt pork at the rind. That is, squares of fat pork are cut around the rind side of—say—an inch or two square and an inch thick. The operative can use this piece of pork as he would a brush and after each five or six brushings he will run this piece of pork across the underside of the stencil wherever the stencil openings occur.

By this treatment, particularly in the use of adhesive diluent applied to the brush just before the brushing in of the color, the color is in each instance distributed in a thin and even film, which dries almost instantaneously, with the result that smearing or smudging in handling does not take place.

All of the steps of my process and the mode of operation and its advantages have

been quite fully pointed out in the foregoing description thereof. Extraordinary reproductions of paintings and other art subjects where color is desirable can be made by its practice. These reproductions exhibit the same characteristics as hand painted water colors. They are, however, produced by common labor and can be made in large editions, which makes it possible to sell them to the purchasing public at an infinitesimal part of the cost of drawings or paintings which are in fact hand colored.

I claim:

1. The process of reproducing pictures and representations of art objects which consists in forming a multiplicity of proofs of the art object upon sheets of paper wherein each proof has the same relation to the edges of said sheets, successively applying said proof sheets to stencil sheets of the same size as and in matching relation with said proof sheets, and, by use of the reproduced marks appearing on the proof sheets as the same are related to the colors of the art object cutting out from said stencil sheet portions thereof corresponding to distinct colors to be applied, which cut-out portions have the same relation to the margins of the stencil sheet as do the corresponding portions of the proof, and thereafter successively applying all of said stencils to a reproduction sheet of the same size as the proof sheets and stencil sheets so that the margins of the stencils and reproduction sheets coincide, and hand brushing over the stencil sheet and upon the reproduction sheet the appropriate color for each said stencil sheet.

2. The process of reproducing pictures and representations of art objects wherein a series of stencils are employed with openings therein corresponding to the several distinct colors to be employed, brushing the colors successively through the openings in said stencils upon the reproduction sheet, using flat-ended brushes for that purpose, lading the brush ends with color, and applying an adhesive diluent to the brush ends just before brushing.

3. The process of reproducing pictures and representations of art objects by the use of stencils and the brushing of distinct colors through each of said stencils wherein the stencil sheets and the reproduction sheets

are formed with corresponding registering devices, successively applying the stencil sheets to a reproduction sheet, always in the same relation thereto by causing said registering devices to coincide, thereafter successively brushing in the colors through the stencil sheets, and covering the back of the stencil with a film of grease to prevent running of the color, and reapplying said film periodically during the use of the stencil.

4. The process of reproducing pictures and representations of art objects wherein a series of stencils are employed with openings therein corresponding to the several distinct colors to be employed, brushing the colors successively through the openings in said stencils upon the reproduction sheet, using flat-ended brushes for that purpose, lading the brush ends with color, applying an adhesive diluent to the brush ends just before brushing, covering the back of the stencil with a film of grease to prevent running of the color, and reapplying said film periodically during the use of the stencil.

5. The process of reproducing pictures and representations of art objects which consists in forming a multiplicity of proofs of the art object upon sheets of paper wherein each proof has the same relation to the edges of said sheets, successively applying of said proof sheets to stencil sheets of the same size as and in matching relation with said proof sheets, and, by use of the reproduced marks appearing on the proof sheets as the same are related to the colors of the art object, cutting out from said stencil sheets portions thereof corresponding to distinct colors to be applied, which cut-out portions have the same relation to the margins of the stencil sheet as do the corresponding portions of the proof, thereafter successively applying all of said stencils to a proof sheet with the cut-out portions of the stencil coinciding with the part of the proof to receive the color of that stencil, and hand brushing over the several stencil sheets and the exposed portions of the proof sheet with the appropriate color for each said stencil sheet.

In testimony whereof I hereunto affix my signature.

GEORGE E. BUZZA.
